UNITED STATES PATENT OFFICE.

HANNIBAL W. RAPPLEYE, OF PHILADELPHIA, PENNSYLVANIA.

METHOD OF AND APPARATUS FOR DRYING MATERIALS.

SPECIFICATION forming part of Letters Patent No. 566,797, dated September 1, 1896.

Application filed January 11, 1894. Serial No. 496,507. (No model.)

To all whom it may concern:

Be it known that I, HANNIBAL W. RAPPLEYE, a citizen of the United States, residing at Philadelphia, county of Philadelphia 5 and State of Pennsylvania, have invented a new and useful Improvement in Methods of and Apparatus for Drying Materials, of which the following is a full, clear, and exact description, reference being had to the accompanying drawings, which form a part of this specification.

My invention relates to a method of and apparatus for drying materials through the medium of hot air. I will first refer to the 15 drawings, in which—

Figure 1 is a view in side elevation, partly in section, on the line $x x$, Fig. 2, of my improved apparatus for carrying out my improved process for drying grain and other 20 materials. Fig. 2 is a plan view of the upper portion of my apparatus and a section on the line $y y$, Fig. 1. Fig. 3 is an end view of the same and a section on the line $z z$, Fig. 1. Fig. 4 is a cross-section on one of the drying 25 cylinders used in my process and forming a part of my apparatus, and a section on the line $1 2$, Fig. 5. Fig. 5 is a section on the line $3 4$ of Fig. 4.

Similar letters of reference indicate corresponding parts.

In the accompanying drawings, $A A' A^2 A^3$ represent the rotary drying-cylinders, which are supported upon wheels a , supported in bearings resting upon supporting-blocks B , 35 resting upon the floor of the building. The frame formed by the uprights and cross-beams may be walled in and floored to form enclosed chambers S for the drying-cylinders. The cylinders are mounted slightly inclined, 40 as shown, adjoining cylinders being inclined in opposite directions. Within the cylinders, as shown in Fig. 4, are the curved wings a' . The cylinders are revoluble, as will be hereinafter described. As the cylinders revolve, 45 the grain or other material to be dried is carried from one end to the other by gravity, the wings a' agitating the mass, so as to expose all portions of the grain to the drying action of the hot air which passes through the 50 cylinders.

The means which I have adopted for im-

parting revolution to the cylinders I will now describe.

On the main driving-shaft of the engine or motor is the main pulley C . On the shaft c' , 55 which extends through the lower chamber from side to side, I mount the pulley C' , pulleys C and C' being connected by a belt. On the same shaft c' I mount the pulley C^2 , connected in like manner with pulley C^3 near 60 the bottom of the chamber, on the shaft of which is the bevel-gear C^4 , located so as to mesh with the bevel-gear C^5 , on the shaft of which is the spur-gear C^6 , adapted to mesh with a gear C^7 on the lowermost drying-cylinder. 65 Near the top of the lower chamber is the pulley C^8 , connected with a third pulley C^9 on the shaft c' . On the shaft of the pulley C^8 is a second pulley C^{10} , connected with a pulley C^{11} , located near the bottom of 70 the second drying-chamber. Between pulley C^{11} and the drying-cylinder A' are shaft and gear connections (substantially like those described in reference to the cylinder A) through which the rotary motion is imparted 75 to the cylinder A' .

In case I desire to use more than two drying-cylinders, the mechanism which I use for imparting motion to them is substantially like that which I have just described for revolving the two lower cylinders, and may be readily understood by an inspection of the drawings. The grain or other material to be dried is deposited in the chamber D . (See Fig. 2.)

To one side of the platform is a conveyer 85 of any desired construction onto which the grain is shoveled or otherwise deposited. I have shown pulleys E and E' and a connecting endless belt E^2 (see Fig. 1) for supporting and conveying the grain. An elevator-shaft 90 extends from the top to the bottom of the framework, at the top of which is a pulley F' and at the bottom the pulley F . An endless chain or belt passes around these pulleys, upon which is mounted an endless series of 95 buckets P . At the end of the conveyer is a chute e , into which the grain from the conveyer is deposited, and which is so disposed near the buckets that the contents of the chute will be deposited therein as the buckets are 100 carried up the shaft.

The pulley C' is connected through the me-

dium of pulleys F^2 , F^3 , F^4 , and F^5 with pulley F^6 by belt connections, as illustrated. Spur-gears f and f' on the shafts of pulleys F' and F^6 , respectively, are set to mesh. Through these pulley, belt, and gear connections the pulley F' is revolved and the elevator operated. By means of belt connection between pulleys E and F the conveyer is operated. As the buckets are elevated and pass around and over the pulley F , their contents are dumped into the chute G , at the end of which is a spout G' , extending into the drying-cylinder. The contents being thus introduced into the uppermost drying-cylinder are gradually carried down through the cylinder into the discharge-spout G^2 , whence the grain is introduced into the cylinder A^2 , through which it travels in a direction opposite to that of the movement of the material in cylinder A^3 . In like manner the material is introduced into and discharged from the cylinder A' and A successively, its final destination being to a conveyer for depositing it in the storage-room or bagging device.

25 I will now describe the means which I have adopted and illustrated for introducing hot air into the cylinders.

From the furnace R extends upwardly the hot-air stack K , terminating at some distance 30 above the top chamber and closed by a damper K^2 . This hot-air stack is lined with fire-brick and is located, as may be best seen by reference to Fig. 2, to one side of the cylinders, and leading from it is the hot-air pipe K' , communicating with the cylinder A^3 at its lower end. Corresponding hot-air pipes K' lead from the stack K to the lower or discharge 35 end of each cylinder. Therefore the hot-air pipes K' communicate with opposite ends of adjoining cylinders, as may be seen by an inspection of Fig. 3.

The exhaust-stack L is located on one side of the cylinders, and on the side opposite the hot-air stack. Exhaust-pipes L' connect it 45 with the upper and grain-inlet end of each cylinder. Therefore these pipes communicate with opposite ends of adjoining cylinders, or, in other words, with corresponding sides of alternate cylinders, as shown in Fig. 3.

50 The pulleys C^X connect with pulleys M' , mounted on shafts which extend into the exhaust-pipe. Mounted on these shafts within the exhaust-pipe are exhaust-fans M , by means of which the air is exhausted from the 55 drying-cylinder into the exhaust-pipe.

The hot-air pipe K' has hinged to it a door k , which may be opened a greater or less degree to reduce to a greater or less extent the temperature of the incoming air from stack K .

60 It is desirable to have the temperature of the air in the upper chambers, where the initial stages of the drying process are carried on, considerably higher than the temperature of the air which I introduce in the lower chambers.

65 By means of the hinged door or valve k I can admit any desired amount of cold air to

each hot-air pipe, and am thus enabled to control the heat and subject the grain in the various cylinders to the precise degree of heat 70 required.

The air is heated in the chambers R above the furnaces N and passes, together with the products of combustion, up the stack K . The hot air which is not deflected into the hot-air pipes communicating with the lower cylinders passes into the hot-air pipe K' , communicating with the cylinder A^3 . Thence it passes through the cylinder, absorbing in its course much of the moisture from the grain, and is finally exhausted by means of the exhaust-fan M into the exhaust-pipe and thence withdrawn through the exhaust-stack. The hot air is in like manner distributed through all the cylinders. It will be further noticed that the course of the air in each cylinder is in an opposite direction from that of the grain. The arrangement by which I effect this results in great economy in carrying out the drying process, for the following reasons: If 80 hot air should be introduced into a cylinder at the grain-inlet, it absorbs at the start considerable moisture and is correspondingly cooled. As it continues its course through the cylinder it absorbs a gradually-decreasing 90 quantity of moisture and becomes correspondingly cooled, and frequently, before it is exhausted, it deposits instead of absorbs moisture, that is, it is likely to moisten somewhat, instead of dry, the drier grain at the opposite or discharge end. In other words, the action upon the grain will not necessarily be a progressively drying one, as a portion of the material may receive moisture that it has already lost. 105

In my apparatus the air will first pass through the comparatively dry grain at the lower end of the cylinder, and very little moisture will be absorbed by the incoming air, most of the moisture being absorbed from the comparatively wet grain toward the opposite end of the cylinder. By this process I guard against the air containing more moisture at any time during the process than the grain through which it circulates. This process is carried out not accidentally in one cylinder, but systematically in all the cylinders. I thus obviate the necessity of redrying grain that after drying may become slightly moistened by absorption from wet air, and avoid 110 the waste of heat thus occasioned. 115

Instead of completely flooring in the main chambers S , I prefer to leave a rectangular open space beneath each cylinder and build around the cylinders a suitable framework T 125 of boards lined with tin. Thus I form a single interior chamber T' , extending from the top to the bottom of my apparatus. At the bottom of this chamber I arrange steam-pipes (not shown) communicating with the exhaust-steam from the engine, whereby I raise the air in chamber T' to a high temperature and thus keep the cylinders always surrounded by hot air. It will be perceived that no par- 130

tion is illustrated at the grain-outlet end of the cylinders for preventing the grain from being discharged by the force of the air-current. The disadvantage incident to the use 5 of an end partition to confine the grain is that it reduces the size of the air-outlet and thus prevents a large volume of air from passing through the cylinder. There is no danger of the air-current ejecting the grain in the 10 upper cylinders, for there the grain is highly saturated with moisture, and consequently very heavy. The exhaust-fans may therefore be revolved rapidly, so as to create as strong a draft as is desirable. In the lower 15 cylinders, however, the grain is drier and consequently lighter, and hence I revolve my exhaust-fans in the lower exhaust-pipes at slower rates of speed and exhaust the air less rapidly, so that the force of the air-current 20 will not be strong enough to carry the grain into the exhaust-pipe.

As previously stated, my process may in many cases be thoroughly carried out by the use of two or more cylinders, although I have 25 shown four.

It is obvious that a vertical arrangement of cylinders need not be adhered to to carry out my process, as the same may be performed equally well with a horizontal arrangement of 30 cylinders.

Having now fully described my invention, what I claim, and desire to protect by Letters Patent, is—

1. In a drying apparatus, in combination, 35 a series of two or more drying-chambers having openings at opposite ends for the reception and discharge of materials to be dried and having end openings for the reception of a heating medium and exhaust-fans at the opposite ends, so connected with a source of power as to revolve at different rates of speed, substantially as described.

2. In a drying apparatus, in combination, 45 a series of two or more drying-chambers having openings at opposite ends for the reception and discharge of materials to be dried, and having openings at the discharge ends of the cylinders for the reception of a heating medium, and exhaust-fans at the opposite 50 ends adapted to revolve at varying rates of speed, substantially as described.

3. In a drying apparatus, in combination, 55 a series of two or more drying-cylinders having openings at opposite ends for the reception and discharge of materials to be dried and having openings at the discharge end for the reception of a heating medium, exhaust-fans at the opposite ends adapted to revolve at varying rates of speed, and a hot-air chamber inclosing the drying-cylinders, substantially as described.

4. In a drying apparatus, in combination, 65 a series of two or more drying-chambers having openings at opposite ends for the reception and discharge of materials to be dried and having end openings for the reception of

a heating medium, and means to force a current of air at a high rate of speed through the first chamber of the series and a current of air at a lower rate of speed through the last 70 chamber of the series, substantially as and for the purpose described.

5. In a drying apparatus, in combination, a series of drying-chambers having openings at opposite ends for the reception and discharge of materials to be dried and having end openings for the reception of a heating medium, and means to force a current of air at a high rate of speed through the first chamber of the series and a current of air at a reduced rate of speed through the last chamber of the series, and currents of air at intermediate rates of speed through the intermediate cylinders of the series, substantially as and for the purpose described. 85

6. In a drying apparatus, in combination, a series of two or more drying-chambers having openings at opposite ends for the reception and discharge of materials to be dried, a main hot-air pipe communicating with a 90 source of heat, a secondary pipe leading from the main hot-air pipe to the discharge end of each cylinder, a pipe leading from the receiving end of each cylinder to an exhaust, and regulating-valves in one or more of the 95 secondary pipes for regulating the temperature of the incoming air, substantially as described.

7. In a drying apparatus, in combination, 100 a series of drying-chambers having openings at opposite ends for the reception and discharge of material to be dried, a main hot-air pipe communicating with a source of heat, a secondary pipe leading from the main hot-air pipe to the discharge end of each cylinder, a pipe leading from the receiving end of each cylinder to an exhaust, regulating-valves in one or more of the secondary pipes for regulating the temperature of the incoming air, and exhaust-fans at the opposite ends so connected with a source of power as to revolve 105 at different rates of speed, substantially as described. 110

8. The hereinbefore-described method of 115 drying materials through the medium of hot air which consists in passing the material through a series of drying-chambers and simultaneously therewith forcing a current of air at a high rate of speed through the first chamber of the series and a current of air at 120 a low rate of speed through the last chamber of the series, substantially as and for the purpose described.

9. The hereinbefore-described method of 125 drying materials through the medium of hot air, which consists in passing the material through a series of drying-chambers and simultaneously therewith forcing a current of air at a high rate of speed through the first chamber of the series, and a current of air at a 130 lower rate of speed through the last chamber of the series, and currents of air at inter-

mediate rates of speed through the intermediate chambers of the series, substantially as and for the purpose described.

10. The hereinbefore-described method of drying materials through the medium of hot air which consists in passing the material through a series of two or more drying-chambers, and simultaneously therewith forcing a current of hot air at a high rate of speed through the first chamber of the series, and a current of air at a lower temperature and at a lower rate of speed through the last chamber of the series, substantially as and for the purpose described.

15. The hereinbefore-described method of drying materials through the medium of hot air which consists in passing the material through a series of drying-chambers, and simultaneously therewith forcing a current of hot air at a high rate of speed through the first chamber of the series, and a current of air at a lower temperature and at a lower rate of speed through the last chamber of the series, and currents of air of medium temperature at intermediate rates of speed through the intermediate chambers of the series, substantially as and for the purpose described.

20. The hereinbefore-described method of drying materials through the medium of hot air which consists in passing the material through a series of drying-chambers and simultaneously therewith forcing a current of air at a high rate of speed through the first chamber of the series and a current of air at a low rate of speed through the last chamber of the series and imparting to each of said currents of air a movement constantly opposite in direction to the direction of movement of the material substantially as and for the purpose described.

25. The hereinbefore-described method of drying materials through the medium of hot air, which consists in passing the material through a series of drying-chambers and simultaneously therewith forcing a current of air at a high rate of speed through the first

chamber of the series, and a current of air at a lower rate of speed through the last chamber of the series and currents of air at intermediate rates of speed through the intermediate chambers of the series, and imparting to each of said currents of air a movement constantly opposite in direction to the direction of movement of the material, substantially as and for the purpose described.

30. The hereinbefore-described method of drying materials through the medium of hot air which consists in passing the material through a series of two or more drying-chambers and simultaneously therewith forcing a current of hot air at a high rate of speed through the first chamber of the series, and a current of air at a lower temperature, and at a lower rate of speed through the last chamber of the series, and imparting to each of said currents of air a movement constantly opposite in direction to the direction of movement of the material, substantially as and for the purpose described.

35. The hereinbefore-described method of drying materials through the medium of hot air which consists in passing the material through a series of drying-chambers, and simultaneously therewith forcing a current of hot air at a high rate of speed through the first chamber of the series, and a current of air at a lower temperature and at a lower rate of speed through the last chamber of the series, and currents of air of medium temperature at intermediate rates of speed through the intermediate chambers of the series, and imparting to each of said currents of air a movement constantly opposite in direction to the direction of movement of the material, substantially as and for the purpose described.

40. In testimony of which invention I have hereunto set my hand.

HANNIBAL W. RAPPLEYE.
